Emery, Barth, Jamieson & Vanney

UNITED STATES PATENT OFFICE.

GEOEGE E. HULSE, OF NEWARK, NEW JERSEY, ASSIGNEE TO THE SAFETY CAR HEATING & LIGHTING COMPANY, A CORPORATION OF NEW JERSEY.

SCREEN.

Application filed January 28, 1919. Serial No. 273,532.

To all whom it may concern:

Be it known that I, GEORGE E. HULSE, a citizen of the United States, and a resident of Newark, in the county of Essex and State 5 of New Jersey, have invented an Improvement in Screens, of which the following is a specification.

This invention relates to apparatus for fluid purification, and with regard to its 10 more specific features, to fluid straining devices.

One of the objects of my invention is to provide fluid straining apparatus which shall be relatively simple and cheap in construction, and reliable in action.

Another object is to provide means of the type set forth of strong and durable construction, and adapted for ready cleaning.

20 Other objects will be in part obvious and in part pointed out hereinafter.

The invention accordingly consists in the features of construction, combinations of elements and arrangement of parts, which 25 will be exemplified in the construction hereinafter set forth, and the scope of the application of which will be indicated in the following claims.

In the accompanying drawings wherein is 30 shown one of various possible embodiments of the several features of this invention,

Fig. 1 is a view in longitudinal section of my strainer, indicating its manner of application between a gas reservoir and a reducing valve.

Figs. 2, 3 and 4 are transverse sectional views along lines 2—2, 3—3 and 4—4 respectively of Fig. 1.

Fig. 5 is a broken sectional view taken 40 along line 5—5 of Fig. 3.

Similar reference characters refer to similar parts throughout the different views of the drawings.

Referring now to the drawings, I have 45 shown a diagrammatic section of a gas reservoir 12, and a reducing valve construction 13, between which my strainer is connected.

As my invention does not reside in either the gas reservoir or the reducing valve, 50 taken by itself, it may simply be noted that the gas reservoir is any desired form of container in which gas may be stored under high pressure.

The reducing valve functions to transmit the gas at reduced pressure after it has been 55 purified by passage through the strainer.

My improved form of strainer preferably consists of two solid and relatively rigid metallic members, a sleeve member 1, and a plug member 2 fitting therein. My sleeve 60 member preferably comprises a metallic tube having a smooth bore as at 3, and having threads 4 at one end, of an internal diameter no less than that of the bore, for a purpose appearing more fully below. Plug 65 member 2 which is fitted in sleeve member 1 is threaded throughout its length, the external diameter of said threads for the part of the length of said plug corresponding to smooth bore 3, being equal to the diameter 70 of said bore, so that the edges of said thread are in close contact with the bore throughout its length as clearly appears in Fig. 5. The end of plug member 2, has threads 4' of somewhat larger diameter to cooperate with 75 threads 4 at the end of sleeve 1, for securing the plug within sleeve.

The entire length of plug 2 except securing end 4' has one side preferably flattened as shown at 5, in Figs. 1 and 3', to leave a 80 relatively small gap or chamber 6 between the surface of bore 3 of the sleeve and said flattened portion, extending substantially the length of the plug. Opposite this flattened portion 5, the plug 2 is preferably 85 similarly flattened as at 7, to leave a gap 8 between the adjacent surface of the tube and said flattened portion. This flattened portion, however preferably extends only to the point 17 in proximity to the inner end of 90 the plug, the threads being left on the plug beyond said point. The smooth inner surface 3 of the tube 1 contacting the edges of the opposite threads at the sides of plug 2, there are thus provided a plurality of ar- 95 cuate passages substantially triangular in section as shown at 11 in Fig. 5, each leading from chamber 8 to chamber 6.

An inclined passage 10 preferably extends from the center of threaded end 4' of plug 100 2 to the adjacent end of chamber 8.

To assemble the parts, it is merely necessary to push the end of my plug 2 into sleeve 1, until the end threads co-operate with threads 4 in the sleeve, whereupon the 105 plug is turned until the threads 4 are

brought into full co-operation. If desired a slot 16 may be provided in the end of the plug for insertion of a screw driver or the like to facilitate assembly.

5 Although as hereinbefore noted, this strainer is of value in various relations, nevertheless it possesses particular advantages in cleansing highly compressed gases such as oxygen, acetylene or Pintsch gas, and the 10 apparatus here diagrammatically shown indicates it in such relation. Briefly stated, the part 12 represents a heavy casing or tank of highly compressed gas, and the casing 13 is that of a reducing valve in which 15 the valve proper, 14, is automatically controlled in the well known manner by a diaphragm 15.

In operation, the gas passes from the reservoir 12, through channel 10, into the space 20 8, which latter constitutes a longitudinally extending intake passage. From passage 8, the gas then travels circumferentially about the plug as shown by arrows in Fig. 3, through the small substantially triangular 25 passages 11, as shown in Fig. 5. The gas after leaving the intake passage 8, is thus divided into twice as many separate channels as there are threads on the plug. In view of the minuteness of channels 11, small 30 particles of solid impurities will be prevented from entering or will be arrested in such passages, thereby cleansing the gas. After emerging from the numerous passages 11, the gas enters the longitudinally extending 35 space 6, from which the purified gas escapes at 9 to the reducing valve.

When the device requires cleaning, it is merely necessary to remove plug 2 from sleeve 1, whereupon all of the passages 40 through which the gas has travelled and in which the impurities are collected will be exposed on its surface. The solid deposit is easily removed from the threads on the surface of the plug, and upon re-inserting the 45 plug within the sleeve, the strainer is again ready for use.

It will thus be seen that there is herein described apparatus in which the several features of this invention are embodied, which 50 apparatus in its action attains the various objects of the invention and is well suited to meet the requirements of practical use.

As many changes could be made in the above construction, and many apparently 55 widely different embodiments of this invention could be made without departing from the scope thereof, it is intended that all matter contained in the above description or shown in the accompanying drawings shall 60 be interpreted as illustrative and not in a limiting sense.

Having thus described my invention, what I claim as new and desire to secure by Letters Patent is:

65 1. A fluid strainer or the like comprising

in combination a substantially rigid sleeve member, a plug member removably fitted into said sleeve member and having a channel formed longitudinally therein to form a passage with the wall of said sleeve member, 70 said channel terminating at a substantial distance from the interior end of said plug thereby to provide an end portion contacting with the wall of said sleeve to a substantial circumferential extent, means 75 forming a channel diametrically opposite said channel and between said plug and said sleeve, a plurality of restricted passages connecting said two channels adapted to strain a fluid passing therethrough, and means for 80 removing said plug member from said sleeve member whereby said end portion of said plug scrapes the interior wall of said sleeve to clean said wall of matter strained from said fluid. 85

2. A fluid strainer or the like comprising in combination a substantially rigid sleeve member, a plug member removably fitted into said sleeve member and having a channel formed longitudinally therein to form a 90 passage with the wall of said sleeve member, means forming a channel diametrically opposite said channel and between said plug and said sleeve, a plurality of restricted passages connecting said two channels adapted 95 to strain a fluid passing therethrough, means associated with the interior end of said plug and shaped to contact with a substantial portion circumferentially of the interior walls of said sleeve member, and means for removing said plug member from said sleeve member whereby said means associated with the end portion of said plug scrapes the interior wall of said sleeve to clean said 100 wall of matter strained from said fluid. 105

3. A fluid strainer comprising in combination a sleeve member, a plug member fitted therein, means for securing said plug to said sleeve, a circuitous path for the passage of a fluid extending in the surface of 110 one of said members and between said two members, said path having longitudinally and circumferentially extending elements, and a plurality of said circumferentially extending elements forming the communication between two adjacent longitudinally extending elements and adapted to strain the fluid passing therethrough. 115

4. A fluid strainer, comprising in combination, a sleeve member, a plug member fitting therein, and a plurality of circuitous paths for the passage of fluid, bounded by adjoining surfaces of said two members, said paths being formed by a substantially helical groove adapted to strain the fluid 125 passing therethrough and means for leading fluid simultaneously to a plurality of said paths.

5. A fluid strainer, comprising in combination, a sleeve member, a plug member fit- 130

- ting therein, and a plurality of circuitous paths for the passage of fluid, bounded by adjoining surfaces of said two members, said paths being formed by a substantially helical groove adapted to strain the fluid passing therethrough and means for leading fluid simultaneously to a plurality of said paths and additional means for tapping fluid simultaneously from a plurality of said paths.
6. A fluid strainer comprising in combination, a sleeve member, a plug member fitting therein, cooperating means on adjoining surfaces for securing said members together, and a threaded portion on said plug member contacting with the inner surface of said sleeve member, said threaded portion being mutilated on diametrically opposite sides along a part of its extent to provide a straining passage for fluid.
7. A fluid strainer comprising in combination a sleeve member, and a threaded plug member inserted therein, said plug member having the thread thereon removed at two substantially diametrically opposite and longitudinally extending portions thereof to provide a straining path for fluid and having the thread at one end thereof extend circumferentially throughout more than one half the circumference of said plug member to form a support for said end of said plug member in said sleeve.
8. A fluid strainer, comprising in combination, a sleeve member, and a plug member threaded therein, parts of the threads on one of said members being removed to provide a plurality of parallel paths for subdividing and straining fluid and formed by the remaining parts of said threads on said one member and the adjacent surface of the other member.
9. A fluid strainer, comprising in combination, a sleeve member, and a plug member threaded therein, parts of the threads on said plug member being removed to provide a plurality of parallel paths for subdividing and straining fluid and formed by the remaining parts of said threads of said one member and the adjacent surface of the other member.
10. A fluid strainer, comprising in combination, a plug member having two threaded portions, a sleeve member having threads near one end adapted to cooperate with one threaded portion of said plug member, the threads on said sleeve member being lacking beyond said end to form a plurality of substantially parallel paths for fluid between said sleeve and the adjoining threads of the other portion of said plug, means for leading fluid to said paths in parallel and means for leading said fluid from said parallel paths.
11. A fluid strainer, comprising in combination, a sleeve member, a plug member fitting therein, a substantially longitudinal intake path and a plurality of relatively fine passages connected to said path, said path and all said passages being bounded by adjoining surfaces of said sleeve and said plug member, and means for allowing exit of said fluid from said passages.
12. A fluid strainer, comprising in combination, a sleeve member, a plug member fitting therein, a substantially longitudinal intake path, a substantially longitudinal exhaust path substantially opposite said first path, and a plurality of relatively fine passages connecting said paths, all said paths and passages being bounded by adjoining surfaces of said sleeve and said plug members.
13. A fluid strainer, comprising in combination, a sleeve member, a threaded plug member fitted therein, said sleeve having smooth cylindrical portions resting against the outer edges of the threads in said plug, a substantially flattened portion cooperating with said sleeve to form an intake passage and adjoining said cylindrical portion, a similar exhaust adjoining the opposite side of said cylindrical portion, and means for securing said plug within said sleeve member.
14. A fluid strainer, comprising in combination, a threaded sleeve member, a threaded plug member screwed therein by cooperating threads near one end, said sleeve member being substantially smooth beyond said threaded portion, the concave surface of said sleeve resting against the outer edges of the threads on said plug, and means to allow exit of fluid from between said latter cooperating elements.
15. A fluid strainer, comprising in combination, a threaded sleeve member, a threaded plug member secured therein by cooperating threads near one end, said sleeve member being substantially smooth beyond said threaded portion and said plug being two based zonal in cross section, the concave surfaces of said sleeve resting against the outer edges of the threads on said plug, and means allowing passage of fluid past said threaded securing means.
16. In a fluid strainer, in combination, a sleeve member, a plug member fitted therein, and a single circuitous path for fluid having included therein two main passages and a plurality of parallel straining passages connecting said two main passages formed in the surface of one of said members and bounded by adjoining surfaces of said members.
17. A fluid strainer comprising in combination a sleeve member having a substantially smooth bore, a threaded plug member therein, means on said plug member adapted to form a pair of substantially oppositely disposed, longitudinally extending

chambers, said plug member having the external diameter of its threads substantially equal to that of said bore whereby said threads form a communication between said 5 chambers, and means for removably securing said members together.

18. A fluid strainer comprising in combination a sleeve member having a substantially smooth bore, a threaded plug member 10 therein, means on said plug member adapted to form a pair of substantially oppositely disposed, longitudinally extending chambers, said plug member having the external diameter of its threads substantially equal 15 to that of said bore whereby said threads form a communication between said chambers, securing threads of larger diameter

near the external end of said plug, and cooperating threads in said sleeve.

19. A fluid strainer comprising in combination, a sleeve member having a substantially smooth bore, a threaded plug member therein, having the external diameter of its threads substantially equal to that of said bore, an intake path leading to said threads 20 on said plug in parallel, an exhaust path communicating with said threads, securing threads of larger diameter near the external end of said plug, and cooperating threads in 25 said sleeve.

In testimony whereof, I have signed my name to this specification this 16th day of January, 1919.

GEORGE E. HULSE.
